(57) **CLAIM**

I claim the ornamental design for a masking device, as shown and described.

DESCRIPTION

FIG. 1 is a first perspective view of a masking device showing my new design.

FIG. 2 is a second perspective view of the masking device shown in FIG. 1.

FIG. 3 is a first plan view of the masking device shown in FIG. 1.

(Continued)

FIG. 4 is a cross-section view of the masking device viewed along section 4-4 shown in FIG. 3.

FIG. 5 is a side elevation view of the masking device shown in FIG. 1; and,

FIG. 6 is a second plan view of the masking device shown in FIG. 1, opposite the first plan view.

1 Claim, 3 Drawing Sheets
